UNITED STATES PATENT OFFICE.

WILLIAM E. HIGHFIELD, OF PHILADELPHIA, PENNSYLVANIA.

MACHINE FOR CHANGING THE ANGLE OF THE FLANGES OF Z AND ANGLE BARS.

SPECIFICATION forming part of Letters Patent No. 399,896, dated March 19, 1889.

Application filed June 14, 1888. Serial No. 277,057. (No model.)

To all whom it may concern:

Be it known that I, WILLIAM E. HIGHFIELD, a citizen of the United States, and a resident of Philadelphia, Pennsylvania, have invented 55 certain Improvements in Machines for Changing the Angle of the Flanges of **Z** and Angle Bars, of which the following is a specification.

My invention consists of certain improvements in the machine forming the subject of my Letters Patent, No. 249,352, dated November 8, 1881, these improvements being fully set forth and specifically claimed hereinafter.

In the accompanying drawings, Figure 1 is 15 a longitudinal section of the machine, partly in elevation. Fig. 2 is an end view of the same, looking in the direction of the arrow, Fig. 1. Fig. 3 is a side view of the complete machine and its driving mechanism. Fig. 4 20 is a side view of part of the machine, showing some of the parts in a different position from that illustrated in Fig. 3; and Figs. 5 and 6 are diagrams illustrating the object of the machine.

25 The machine is similar in its general construction and operation to that forming the subject of my before-mentioned Letters Patent, having two pairs of conical or beveled rolls, A A' and B B', carried by shafts a a' 30 and b b', geared together by bevel-wheels c, and adapted near their outer ends to boxes d, pivoted to suitable bearings on the opposite side frames, D, of the machine, the inner ends of the shafts being adapted to boxes d', which 35 are guided in slots d'', formed in plates secured to the inner sides of said frames D.

To fixed bearings in the lower portion of the machine is adapted a shaft, m, having cams or eccentrics n, which act upon guided 40 yokes p, connected by rods s to the bars carrying the boxes d' of the roll-shafts, so that as said shaft n is turned the rolls A A' and B B' may be caused to rise and fall, the pivoting of the outer boxes, d, of the roll-shafts 45 permitting such movement.

The present machine is driven by means of a shaft, F, adapted to suitable bearings on one of the side frames, D, of the machine, and provided with pulleys f for receiving a driving-belt from a pulley on any adjacent coun-

ter-shaft, the shaft F having spur-pinions t, which engage with spur-wheels t', adapted to turn freely upon sleeves G, projecting from transverse bars G' at the ends of the machine. Each of these spur-wheels has on its outer 55 face two projecting fingers, w w, those of one wheel engaging with a projecting arm, x, carried by the outer end of the shaft a, and those of the other wheel engaging with a similar arm projecting from the shaft b, so that 60 rotary movement is imparted to said shafts without any interference with the swinging movement of the same, for the diameter of the bearing-sleeves G and of the openings in the spur-wheels t' is so much greater than the 65 diameter of the shaft that a vertical slot, y, can be formed in each sleeve G to permit the swinging of the shaft.

The opposite side frames, D D, of the machine have central openings, so as to expose 70 the rolls A A' B B', for permitting the feeding of the bars thereto, and the upper rolls, A' B', are narrower than the lower rolls, A B, so as to permit the passage of bars of **Z** shape 75 between the rolls, instead of limiting the capacity of the machine to simple angle-bars, as before.

It will be observed that in the present machine the lower rolls are of sufficient width to provide a support for the central web of the 80 bar throughout its entire width, while the upper rolls are such as not to interfere with the outer flange of the bar.

The shaft m has a worm-wheel, k, which engages with a worm, i, on a vertical shaft, h; 85 but in order that the action of the machine may be more directly under the control of the attendant than before I provide the upper end of the said shaft h with a hand-wheel, h', by turning which in one direction or the other 90 the cam-shaft m may be actuated, so that its cams will cause the raising or lowering of the roll-shafts and rolls, thus causing a change in the relation of the rolls to each other, and a corresponding change in the character of the 95 angular pass presented by said rolls, as shown in Figs. 3 and 4 and by the diagrams, Figs. 5 and 6.

The flanges of the bar are normally at right angles to each other, as shown in Figs. 1 and 100

5, and in starting the operation the rolls of the machine present a right-angled pass, as likewise shown in said figures.

When it becomes necessary to change the 5 angle of the flange which is being acted upon, the hand-wheel h' is turned, so as to impart such movement to the cam-shaft m as to cause a depression of the inner ends of the roll-shafts $a' a' b' b'$, thus changing the angular position 10 of the acting faces of the rolls in respect to a vertical line and causing a like change in the angle of the pass formed by said rolls, as shown, for instance, in Figs. 4 and 6. The hand-wheel h' is operated rapidly or 15 slowly, depending upon whether the angle is to be changed suddenly or gradually, and the operation of the hand-wheel is continued until the change of angle is as great as desired.

In my former patented machine the cam-shaft at the bottom of the machine had a worm-wheel which was operated by a worm on a vertical shaft at one side of the machine, and this vertical shaft had a cone-drum which received a belt passing around another cone-drum 25 on a vertical shaft at the end of the machine, the latter shaft being driven by gearing from one of the roll-shafts. The objection to this plan was, mainly, the inaccuracy in the operation of the cam-shaft which it 30 caused, for as the power to operate the cam-shaft was transmitted through the medium of the belt and cone pulleys there was always a liability of the belt to slip on the pulleys, and the operator never knew exactly whether the 35 angle-iron was being properly beveled.

In the present machine, therefore, I secure a hand-wheel directly on the vertical shaft carrying the worm which gears into the worm-wheel on the cam-shaft, so that there is a positive 40 and definite connection between this hand-wheel and the cam-shaft, and no liability of any of the parts between the hand-wheel and cam-shaft to slip; hence, whenever the operator turns the hand-wheel in 45 one direction or the other he knows to a certainty that there has been a corresponding operation of the cam-shaft and a desired change in the position of the rolls. Not only, therefore, does the present arrangement render 50 the machine certain in its action, whereas it was before more or less uncertain, but it also simplifies the construction of the machine, as it dispenses with the second vertical shaft, the cone-drums, and the connecting-belt.

It is customary to mount the machine di-

rectly in front of the furnace in which the bars are being heated, so that on issuing from the furnace the bars may be passed directly between the rolls; but it is advisable to move 60 the machine away from the front of the furnace when it is desired to use the latter for other purposes. For this reason I make the driving-shaft with a detachable section, F' , between that section to which power is applied and 65 that section which is geared to the machine, so that on removing this intermediate section the machine may be shifted bodily on its supporting sills or rails, so as to be moved away from the front of the furnace, that section of the counter-shaft carried by the machine being then, if desired, coupled to the driving-section, if it is desired to use the machine for acting upon short pieces of bar, which can be heated without the use of the 70 main furnace.

Having thus described my invention, I claim and desire to secure by Letters Patent—

1. The combination of a pair of beveled rolls and their shafts adapted to pivoted 80 boxes, with an arm projecting laterally from the shaft of one roll, and a driving-wheel having longitudinally-projecting fingers for engaging with said arm, and a central opening of larger diameter than the shaft, whereby the 85 swinging of the latter on its pivots is permitted, all substantially as specified.

2. The combination of a pair of bevel-wheels having shafts adapted to pivoted boxes, an arm projecting from the shaft of one roll, 90 a driving-wheel having projecting fingers engaging with said arm, and a sleeve serving as a bearing for said wheel and having a vertical slot for the passage of the shaft, all substantially as specified. 95

3. The combination of the two pairs of beveled rolls and the pivoted shafts carrying the same, a shaft having cams, and connecting-rods whereby said cams are caused to act on the roll-shafts, a counter-shaft, worm-gearing 100 whereby the counter-shaft is caused to operate the cam-shaft, and a hand-wheel whereby said counter-shaft may be directly operated, all substantially as specified.

In testimony whereof I have signed my name 105 to this specification in the presence of two subscribing witnesses.

WILLIAM E. HIGHFIELD.
